UNITED STATES PATENT OFFICE.

AUGUST E. SANDSTROM, OF NEW YORK, N. Y.

DESIGN FOR A TOY TOP.

55,084.

Specification for Design.

Patented May 4, 1920.

Application filed June 30, 1919. Serial No. 307,872. Term of patent 14 years.

To all whom it may concern:

Be it known that I, AUGUST E. SANDSTROM, a subject of the King of Sweden, having declared my intention of becoming a citizen of the United States, residing in the borough of Manhattan, city, county, and State of New York, have invented a new, original, and ornamental Design for Toy Tops, of which the following is a specification, reference being had to the accompanying drawings, forming part thereof.

Figure 1, is a top plan view of a toy top showing my new design;

Fig. 2, is a side elevation thereof; and
Fig. 3, is a bottom plan view of the under side thereof.

I claim:

The ornamental design for a toy top, as shown.

AUGUST E. SANDSTROM.
